UNITED STATES PATENT OFFICE.

LIZZIE PICKARD, OF TORONTO, CANADA.

DESIGN FOR A SINK-STRAINER.

SPECIFICATION forming part of Design No. 23,199, dated April 17, 1894.

Application filed February 13, 1894. Serial No. 500,078. Term of patent 14 years.

To all whom it may concern:

- Be it known that I, LIZZIE PICKARD, a subject of the Queen of Great Britain, residing at Toronto, in the county of York, Province of Ontario, Canada, have invented and produced a new and original Design for Sink-Strainers, of which the following is a specification, reference being had therein to the accompanying drawing.
- 10 This design is intended for a strainer adapted to be set in the corner of a sink, and the essential features thereof are shown in the accompanying drawing which shows a perspective view of my strainer.
- 15 Referring now to said drawing by letters— A represents the front of said strainer which is curved and perforated with fine holes, which front is connected to straight side pieces B B, arranged in the form of a right

angle. These parts terminate below in a 20 point as shown at C, so that while the top of the strainer forms a quadrant, the whole strainer tapers from the top down to a point C. Around the edge of the front is a bead which adds to the ornamental effect and strengthens 25 the rim. At each corner is a loop D.

What I claim as new is—

The design for a sink strainer, substantially as herein shown and described.

In testimony whereof I affix my signature in 30 presence of two witnesses.

LIZZIE PICKARD.
